MERCANDISE DISPLAY STAND

Anthony Mohr, Chicago, Ill.

Application November 14, 1952, Serial No. 22,280

Term of patent 7 years

(Cl. D80—9)

To all whom it may concern:

Be it known that I, Anthony Mohr, a citizen of the United States, residing at Chicago, in the county of Cook, and State of Illinois, have invented a new, original, and ornamental Design for a Merchandise Display Stand, of which the following is a specification, reference being had to the accompanying drawing, forming part thereof.

The broken lines shown in Figures 1 and 2 are for illustrative purposes only and the parts represented thereby are no part of the design.

I claim:

The ornamental design for a merchandise display stand, substantially as shown and described.

ANTHONY MOHR.
